(57) **CLAIM**

The ornamental design for a protective shield for a computer keyboard, as shown and described.

DESCRIPTION

FIG. 1 is a perspective view of a protective shield for a computer keyboard;

FIG. 2 is a front view thereof, but without the environment shown in broken lines;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of a monitor and keyboard is included for the purpose of illustrating environment and forms no part of the claimed design.
